DESIGN FOR A COUNTER DISPLAY RACK FOR BAGGED PEANUTS

Robert B. Wemyss, Louisville, Ky.

Application October 27, 1944, Serial No. 116,009

Term of patent 7 years

(Cl. D80—9)

To all whom it may concern:

Be it known that Robert B. Wemyss, a citizen of the United States, residing in Louisville, county of Jefferson, State of Kentucky, has invented a new, original, and ornamental Design for a Counter Display Rack for Bagged Peanuts, of which the following is a specification, reference being had to the accompanying drawing forming part thereof.

The figure is a perspective view of a counter display rack for bagged peanuts showing my new design, the opposite end of which is the same as the end shown.

I claim:

The ornamental design for a counter display rack for bagged peanuts, substantially as shown and described.

ROBERT B. WEMYSS.
